UNITED STATES PATENT OFFICE.

FRANK F. B. CHAPMAN, OF WINCHESTER, MASSACHUSETTS.

POULTRY TRAP-NEST.

No. 880,778.

Specification of Letters Patent.

Patented March 9, 1908.

Application filed December 1, 1905. Serial No. 289,904.

To all whom it may concern:

Be it known that I, FRANK F. B. CHAPMAN, a citizen of the United States, residing at Winchester, in the county of Middlesex and State of Massachusetts, have invented a certain new and useful Improvement in Poultry Trap-Nests, of which the following is a full, clear, and exact description.

The object of this invention is to provide a poultry nest, which is also capable of use as a trap, of such character that when the hen enters the nest the door is automatically locked against the entrance of another hen, and which door may be locked also to prevent the egress of the imprisoned hen.

The invention consists of a trap nest inclosed on all sides, and having a swinging door, so that the nest may be rendered practically dark, the door being hinged in such way as to be capable of swinging inwardly to admit the hen into the nest and of swinging outwardly to permit her exit therefrom, and also provided with means whereby after a hen is once imprisoned, no other hen may enter the same nest, and the imprisoned hen may be locked in, or allowed to go out of the nest as may be desired, all as I will proceed now more particularly to set forth and finally claim.

In the accompanying drawings illustrating the invention, in the several figures of which like parts are similarly designated, Figure 1 is a front elevation of a series of three combined nests, the left-hand door being set open for the entrance of the hen, and the door in the center being closed to prevent the ingress of another hen, while permitting the egress of the imprisoned hen, and the door at the right-hand being locked both against the entrance of another hen and the escape of the imprisoned hen. Fig. 2 is a top plan view with a portion of the top broken away. Fig. 3 is an end view with a portion of the end wall broken away, and this view serving to illustrate the construction of either a series of nests, as in Figs. 1 and 2, or a single nest, as shown in the next view. Fig. 4 is a front elevation of a single nest.

Whether the nest be composed of a series of cells, as in Figs. 1 and 2, or of a single cell, as in Fig. 4, it has a tight bottom 1, back 2, and ends 3, and the top is composed of a fixed portion 4, and a hinged cover 5, hinged to the fixed portion 4 and adapted to be opened so as to gain access to the interior of the cell or

nest. The front has a fixed portion 6, and the door 7 is hung from the fixed top portion 4. The door 7 is suspended from the fixed portion 4 by means of hinges 8, of such construction as will admit of the door swinging freely within the nest and outside of the nest so as, respectively, to permit the hen to enter the nest by pushing the door inward with her, and also to permit the hen to escape from the nest by pushing the door outwardly with her. Each cell is provided with a separate door, and each door is provided with a notch 9 in its lower edge, and preferably centrally, in which the hen extends her neck in coming out and going into the nest.

One edge of the door is provided with a spring or other suitable dogging device 10, which normally projects from the side edge of the door into line with a stop 11 fixed on the inside of the side wall of the nest. The device 10 is springy, and thus may ride over stop 11 as the door swings outwardly and these devices 10 and 11 serve to arrest the inward movement of the door and obviously lock the door against the entrance of a hen from the outside. The dogging device 10 is accessible to an attendant from the outside so that it may be pressed back by the thumb of the attendant to enable it to pass the stop whenever desirable.

12 is a hook pivoted at 13 to the inside of the side wall eccentrically with relation to the center of motion of the door, and having the portion 14 in frictional contact with the side or end wall and its free end deflected, as shown in Figs. 1 and 4, so as to extend into the path of movement of the door. This deflected portion of the hook 12 has its L-shaped end 15 so arranged that when the door is manually pushed inwardly, as in Fig. 3, its lower edge may be engaged by the end 15 and the door held in this position so as to invite the entrance of a hen. But when in this position, the door is not fully open, and as the hen enters she must push the door in with her into approximately the dotted line position shown in Fig. 3, and in doing so the hook is pushed into the dotted line position indicated for it and thereby freed from engagement with the door, so that after the hen passes fully into the cell, the door is free to swing back or outwardly, and this occurring, the door is locked against further inward swing by the engagement of its dogging device 10 with the stop 11, but the door is

free to swing outward to permit the escape of the hen.

If for any reason it be desired to imprison the hen within the nest, then a movable stop, such as a turn-button 16 is turned up as in the right-hand cell of Fig. 1, or as in Fig. 4, to lock the door against outward movement. When the door is closed, the cell is comparatively dark, and thus tends to correct the habit some hens have of eating their eggs. It will be observed that after a hen leaves the nest, it is impossible for another hen to enter the same nest until the door has been reset by the attendant. Where a nest is composed of a series of cells, each cell is separated from the other by a partition 17.

By providing the door with means to lock it against the entrance of a second hen, or the egress of the hen which has entered the cell, it is possible for breeders to note the relative prolificness of their hens, and it is also possible to identify the eggs of each individual hen.

What I claim is:—

1. A poultry trap nest, having a swinging entrance door, a pivoted hook for supporting the door partially open inwardly and adapted to be disengaged from the door, upon further inward movement of the door, and an independent automatically operating door-locking mechanism for locking the door in closed position against inward movement only, after the hen enters the nest and releases the door from its supporting hook by further inward movement of the door, said locking mechanism serving the double purpose of preventing the entrance of another hen into the same nest and the entrance of any hen into the nest after an occupant has left the nest.

2. A poultry trap nest, having an inwardly and outwardly swinging entrance door, a pivoted hook for supporting the door partially open inwardly and adapted to be disengaged from the door by further inward movement of the door, and an independent locking mechanism for automatically locking the door in closed position against inward movement only, after the hen enters the nest and releases the door from its supporting hook by further inward movement of the door, said locking mechanism serving the purpose of preventing the entrance of another hen into the same nest and the entrance of any hen into the nest after an occupant has left the nest, the door being capable of being opened from the inside by an outcoming hen.

3. A poultry trap nest, having an inwardly and outwardly swinging entrance door, a pivoted hook for supporting the door partially open inwardly and adapted to be disengaged from the door by further inward

movement of the door, and an independent spring dogging device and a stop therefor 65 for automatically locking the door in closed position against inward movement only, after the hen enters the nest and releases the door from its supporting hook by further inward movement of the door, said dogging 70 device and stop serving the double purpose of preventing the entrance of another hen into the same nest and permitting the egress of an imprisoned hen.

4. A poultry trap nest, composed of several cells, each cell having an inwardly and outwardly swinging door, a pivoted hook in each cell for supporting the door partially open inwardly for the entrance of a hen, said door being capable of being released from its supporting hook by further inward movement 80 of the door upon the entrance of the hen to permit the door to close, and an automatic locking mechanism for locking the thus released door in closed position against 85 inward movement, and at the same time allowing the door to swing outward to permit the exit of the imprisoned hen.

5. A poultry trap nest, composed of several cells, each cell having an inwardly and outwardly swinging door, a pivoted hook in each cell for setting the door partially open inwardly for the entrance of a hen, said door being capable of being wholly disengaged from said hook by the ingoing hen pushing 95 the door inwardly to permit the door to close, and a dogging mechanism for each door independent of the setting mechanism for locking the door in closed position against inward movement and permitting outward 100 movement of the door for the free exit of the imprisoned hen.

6. A poultry trap nest, composed of several cells, each cell having an inwardly and outwardly swinging door, a pivoted hook 105 for each cell adapted to engage the door to set it partially open inwardly for the entrance of a hen, said door being capable of being wholly disengaged from the hook by the ingoing hen pushing the door inwardly 110 to permit the door to close, a dogging mechanism for each door for locking the door against inward movement when released, and an independent movable stop for locking each door against outward movement by 115 the imprisoned hen.

7. A poultry trap nest, having a swinging entrance door, a pivoted hook adapted to engage the door to set it partially open inwardly and adapted to be disengaged from the door by further inward movement of the door, and a locking mechanism whereby the door when released from its setting hook by further inward movement of the door may be automatically locked in closed position 125 against inward movement only, after the hen

enters the nest, said locking means serving the double purpose of preventing the entrance of a second hen into the same nest and the entrance of any hen into the nest after an occupant has left the nest, and a hinged cover for gaining access to the interior of the nest.

In testimony whereof I have hereunto set my hand this 29th day of November A. D. 1905.

Corrections in Letters Patent No. 880,778.

It is hereby certified that in Letters Patent No. 880,778, granted March 3, 1908, upon the application of Frank F. B. Chapman, of Winchester, Massachusetts, for an improvement in "Poultry Trap-Nests," errors appear in the printed specification requiring correction, as follows: In line 69, page 1, after the word "her" the words *head and* should be inserted, and the name of the second witness should read *C. H. Chapman* instead of "C. C. Chapman"; and that the said Letters Patent should be read with these corrections therein that the same may conform to the record of the case in the Patent Office.

Signed and sealed this 24th day of March, A. D., 1908.
